UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

TRIPLEX WEB PRESS

Application filed August 4, 1923, Serial No. 655,776. Renewed April 6, 1929.

This invention relates to a perfecting web press capable of employing three webs at a time parallel with each other.

The principal objects of the invention are 5 to provide for the supplying of the three webs to the press, printing on both sides of the webs that pass through the printing couples, and leading the webs from the press into the cutting and folding mechanism and through 10 to the delivery. The invention also involves improvements in details of the means for driving the cutting, collecting and folding mechanism and delivery fans, and especially the driving of the folding and cutting cylinders absolutely positively from the printing couple and eliminating back lash which would break the web, and the driving of the drag rolls and other positively driven parts of the folding machine directly from the shaft 15 20 25 30 35 40 45 50 55 60 65 70 75 80 85 90 95 100

Other objects and advantages of the invention will appear hereinafter.

Reference is to be had to the accompanying drawings in which

Fig. 1 is a central longitudinal sectional diagrammatic view of a double perfecting web press constructed in accordance with this invention;

Fig. 2 is a diagrammatic side view of the press showing the folders, deliveries, etc. and indicating some of the rollers in cross section to indicate their position;

Fig. 3 is a plan of the same;

Fig. 4 is an enlarged plan view similar to Fig. 3 at one end of the machine;

Fig. 5 is an end view of the same on further enlarged scale;

Fig. 6 is a plan on the same scale as Fig. 5 showing original and final positions of the web rolls;

Fig. 7 is an end view of the folding and delivery mechanism to show the method of driving them;

Fig. 8 is a side view of the same, and

Fig. 9 is a similar view of a portion of the same showing a different method of connecting up the delivery fan.

The invention, although not necessarily confined thereto, is shown as applied to a double press having two complete sets of web-perfecting couples comprising plate cylinders 10 and impression cylinders 11. These are indicated in the usual way as receiving ink from the fountain 12 through a fountain roll 13, delivering it to an ink cylinder 14 by a ductor roll 17 and distributing it thereon by distributing rolls 15. The usual form rolls 16 are shown for applying the ink to the plates. These parts, of course, are shown in four places on the particular press illustrated. The webs W are led through the printing part of the machine in the usual way, being taken from three web rolls 18 at each end in this case. The three webs from each end are fed inwardly toward the center through the printing couples and fed over the compensating rolls 19. From the compensating rolls the three webs from each end, each handled separately, are brought into the folders over the formers 20.

It will be understood that the several webs can be taken from the compensating rolls 19 to the formers and through them in several different manners. Some of these are indicated by full and dotted lines respectively in Fig. 2. The webs from one end of the press can be brought over in contact with guide rolls 21 to the former normally used for the other end of the machine if desired as shown in dotted lines. Of course, the opposite operation could be accomplished also. Also instead of taking the web right down through the collecting mechanism from the former on the left-hand end of the press, the same can be carried over to the other collecting mechanism as shown in full lines in Fig. 2.

For the purpose of operating the folding mechanism in exact unison with the printing couples, I have provided one of each pair of

impression cylinders 11, or rather its shaft, with a coupling device 22 and coupled it directly to the shaft 23 of the folding cylinder 24. For this purpose I place the shaft of the impression cylinder and the shaft 23 of the folding cylinder in alignment. They are positively coupled together so that they must rotate in unison and the shaft 23 therefore becomes the main driving shaft of the collecting, folding, and delivering mechanism as well as the press if driven directly from a motor as indicated in Fig. 3. This shaft is provided with a sprocket and sprocket chain 25 for driving, through gears 26, two drag rolls 27 on the same shaft. There is also a gear 28 on the shaft 23 driving the gear 29 on the shaft of the cutting cylinder 30 so as to drive these two cylinders in perfect unison as usual. The press can be driven from a shaft 55 at the other side if desired as indicated by dotted lines in Fig. 3. In either case back lash is eliminated so that no breakage from the web from this cause need take place.

25 The cutting cylinder shaft 31 is also provided with means for driving through a sprocket chain 32 the nipping rolls 33, and insuring their being driven positively in perfect unison. It is also provided with 30 sprocket wheel and chain 34 for driving the delivery fan 35 on its shaft 36. The folding rolls 37 are driven by gears from a gear 28. In this way all these parts are positively driven in exact time with the press.

35 I have also provided for a very simple change when it is desired to drive the fan 35 in the opposite direction, so that instead of delivering to a set of delivery tapes 38 on one side of the fan, the products can be delivered to a different set of tapes 39 on the opposite side. For this purpose the main driving shaft 23 is provided with a sprocket wheel adapted to receive the chain 34. Therefore, instead of connecting the parts up as shown 40 in Fig. 8 just described above the sprocket chain 34 is connected with the shaft 23 directly, and the fan is taken off its shaft 36 and reversed thereon. Also the driving shaft 49 for the delivery tapes is wound over to the left. Then the parts are driven as shown in 45 Fig. 9 and the products delivered on the right side instead of on the left. This is readily accomplished as will be obvious from the fact that the shafts 23 and 31, being geared directly together by two gears, one on each shaft, rotate in opposite directions. The shaft 31 rotates faster than the shaft 23, and consequently the two sprocket wheels on these shafts adapted to receive the chain 34 are of 50 correspondingly different sizes so as to keep the speed of the fan the same in both cases. The deliveries are driven in either case from the shaft 36.

55 The usual forming rolls 40 are employed, but they are not positively driven.

In order to supply three webs to a single printing couple and not make the printing cylinders unduly long, difficulty is encountered owing to the fact that of course the supports for the web rolls involve certain solid parts which take up an appreciable amount of room at each end of each web roll. If three web rolls were mounted end to end on their ordinary supports there would be a wide space between the edges of the webs. It would be poor economy to do this and widen out the press unnecessarily for it would necessitate making all the rolls and cylinders very long and they would tend to spring and vibrate at points between their bearings.

70 In order to reduce the spaces between the edges of the webs as much as possible, and therefore, reduce the width of the press and the length of the printing cylinders and other rolls and cylinders of the press to a minimum, I provide means shown in Figs. 4, 5 and 6, for supporting the three web rolls 18 at each end of the press. The middle web roll is mounted as usual, on a pair of standards 41 having bearings for its shaft. The 75 shaft is provided with a pulley 42 by which it may be turned to get it up to web speed. These standards are provided with projections 43 having a gradually upwardly curved supporting surface or track thereon. This permits of rolling the web roll in on the floor from the rear, and engaging the ends of its shaft with these surfaces while the roll rests on the floor. Then the shaft is rolled up these 80 inclined cam surfaces into the open-topped 85 bearings taking the roll with it.

I also provide arms 44 on these standards projecting upwardly and having bearings for a pair of rods 45 to support a web guide roll 46. Springs 47 are employed to hold the roll 46 up so that the web W can be guided 90 up away from the surface of the roll and kept taut.

95 This mechanism, as stated, occupies so much space sideways that I do not wish to 100 put all three rolls in axial alignment and lose the space occupied by the supporting mechanism. In order to avoid this I bring up the two side rolls into the dotted line positions indicated in Fig. 6. Then I provide 105 for locating them in such a way that their edges will come over close to the opposite edges of the first roll above mentioned.

110 For this purpose I provide two pairs of tracks 50 located in alignment nearer the 115 press than the central web roll 18. On these tracks I locate a pair of carriages 51 having rollers 52 resting on the tracks. Each of these carriages is provided with a standard 120 53 having an open bearing like the standard 41 and provided with hinged loading levers 54. These carriages are brought out to the 125 side in registration with the dotted line position of the web roll, which is the actual position of the roll when resting on the floor.

Then the levers 54 are turned down as shown in Fig. 5, the web roll rolled up on the floor until its shaft engages these arms. Then these arms, either by hand or otherwise, are turned upwardly to lift the roll and roll it over into its two bearings in the standards 53.

When the side web roll is mounted on its carriage in this way, the carriage is rolled toward the central roll to the position shown in Fig. 6 and also in Fig. 4. The end of the carriage comes up against pins 48 which serve as stops for limiting its inward position so that it will register with the printing mechanism in the press. It will be obvious that both of the side rolls are manipulated in the same way, and that they are supported on their carriages while they are being unwound. The three are in staggered relationship.

I have also shown a tension roller 56 mounted on a bracket on the frame of the press for guiding the web from this web roll.

In this way a simple and convenient means is provided whereby three web rolls can be located in proper position to deliver simultaneously to a three web width printing machine without necessitating the making of the printing machine of excessive width.

Although I have illustrated and described only a single form of the invention and shown only a few ways of using it, I am aware of the fact that modifications can be made in the relative arrangements and construction of the parts, and that the parts can be manipulated in other ways to lead the web through as desired without departing from the scope of the invention as expressed in the claims. Therefore, I do not wish to be limited in these respects but what I do claim is:—

1. In a perfecting web press, the combination with two sets of printing couples, each set comprising two pairs of printing cylinders, all of said cylinders being of a length to receive and print three separate newspaper webs simultaneously, and means for feeding three webs side by side to either set of couples separately, of a pair of folding, collecting and delivering devices, and means whereby each web from either set of couples can be directed to either folding, collecting and delivering device.

2. In a printing press, the combination of a set of printing couples, each comprising impression and plate cylinders of a length capable of printing simultaneously three newspaper webs separate from each other and means for guiding each of said webs separately from the last printing couple, with a cutting, folding, and delivering mechanism comprising a folding cylinder, and a shaft on which said folding cylinder is mounted coupled directly to the end of the shaft of one of the printing couple cylinders.

3. In a printing press, the combination of a printing couple, with a folding cylinder,

and a shaft on which said folding cylinder is mounted coupled directly to the end of the shaft of one cylinder of the printing couple.

4. In a printing press, the combination with a web perfecting set of printing cylinders, a former, a folding and cutting cylinder geared together, and means for coupling the shaft of one of said cylinders directly to the shaft of one of the cylinders of said couples.

5. In a printing press, the combination with a web perfecting set of printing cylinders, a folding cylinder and a cutting cylinder geared together, means for coupling the shaft of one of said cylinders directly to the shaft of one of the impression cylinders of said couples, of a delivery fan and means for driving the delivery fan either from the shaft of the folding cylinder or the shaft of the cutting cylinder to reverse the direction of rotation of the fan.

6. In a cutting, collecting and delivering device, the combination with a folding cylinder, a cutting cylinder, and a shaft for each, and means for gearing said shafts together to cause either to rotate positively with the other, of a delivery fan shaft, a fan thereon which can be removed from the shaft and turned around to deliver on either side thereof, a sprocket chain for driving said fan, and sprocket wheels on the folding cylinder shaft and cutting cylinder shaft respectively for receiving the sprocket chain and driving the fan.

7. In a cutting, collecting and delivering device, the combination with a folding cylinder, a cutting cylinder, and a shaft for each, of a delivery fan shaft, a fan thereon which can be removed from the shaft and turned around to deliver on either side thereof, a sprocket chain for driving said fan, and sprocket wheels on the folding cylinder shaft and cutting cylinder shaft for receiving the sprocket chain and driving the fan, the sprocket wheel on the folding cylinder shaft being just as much larger than the sprocket wheel on the cutting cylinder shaft as the folding cylinder is larger than the cutting cylinder, whereby the delivery fan can be driven in one direction from one shaft and in the other direction from the other shaft at the same speed.

8. In a folder, the combination with the folding and cutting cylinders geared together, and means for driving one of them directly from a printing couple, of a delivery fan and means for driving the fan adapted to be connected with either of said cylinders.

9. In a folder, the combination with the folding and cutting cylinders geared together, means for driving one of them directly from a printing couple, of a drag roll, delivery fan, and nipping rolls, and means for driving them from one of said cylinders.

10. In a folder, the combination with the folding and cutting cylinders geared to-

gether, means for driving one of them directly from a printing couple, of a drag roll, and means for driving the drag roll positively from one of said cylinders.

- 5 11. The combination with a web press having impression and plate cylinders of a length sufficient to receive three separate newspaper webs thereon at once and print the same simultaneously, of means for supporting a
10 web roll in stationary position to supply the central web, and means for supporting two side web rolls for supplying the side webs in a position out of alignment with the central web roll but their ends adjacent to the
15 end thereof.
12. The combination with a perfecting web press having printing couples long enough to receive and simultaneously print on three separate webs, of means for supporting a
20 central web roll for supplying the middle web and means for supporting two side web rolls out of axial alignment therewith and the supporting means therefor being offset from the supporting means for the central roll a distance greater than the radius thereof but with
25 their ends adjacent to the ends of the central web roll.

13. In a perfecting web press, the combination with two sets of printing couples, each
30 set comprising two pairs of printing cylinders, all of said cylinders being of a length to receive and print a plurality of separate newspaper webs simultaneously, and means for feeding the webs side by side to either
35 set of couples separately, of a pair of folding devices having their driving shafts coupled directly to one of the shafts of the respective printing couples, and means whereby each web from either set of couples can be
40 directed to either folding device.

In testimony whereof I have hereunto affixed my signature.

HENRY A. WISE WOOD.
